DESIGN FOR A BLOUSE

Irving Geist, New York, N. Y.

Application September 21, 1935, Serial No. 58,711

Term of patent 3½ years

To all whom it may concern:

Be it known that I, Irving Geist, a citizen of the United States, residing in the city, county, and State of New York, having invented a new, original, and ornamental Design for a Blouse, of which the following is a specification, reference being had to the accompanying drawing, forming part thereof, in which

Fig. 1 is a front view of the blouse embodying my design,

Fig. 2 is a rear view of the blouse shown in Fig. 1.

The front of the blouse is pleated, indicated by the vertical lines in Fig. 1.

I claim:

The ornamental design for a blouse as shown and described.

Signed at New York, in the county of Kings, and in the State of New York, this 14th day of September, 1935, A. D.

IRVING GEIST.
